(57) **CLAIM**

The ornamental design for a birdhouse, as shown and described.

DESCRIPTION

FIG. 1 is a front perspective view of a first embodiment of a birdhouse according to the new design;
FIG. 2 is a rear perspective view of the birdhouse of FIG. 1;
FIG. 3 is a front view of the birdhouse of FIG. 1;
FIG. 4 is a rear view of the birdhouse of FIG. 1;
FIG. 5 is a right side view of the birdhouse of FIG. 1;
FIG. 6 is a left side view of the birdhouse of FIG. 1;
FIG. 7 is a top plan view of the birdhouse of FIG. 1; and,
FIG. 8 is a bottom plan view of the birdhouse of FIG. 1.
The broken lines in the drawings illustrate portions of the birdhouse that form no part of the claimed design.
